UNITED STATES PATENT OFFICE.

JULIA LUEDERS, OF ST. LOUIS, MISSOURI.

DESIGN FOR A CHAIR.

SPECIFICATION forming part of Design No. 17,375, dated June 7, 1887.

Application filed March 12, 1887. Serial No. 230,729. Term of patent 14 years.

To all whom it may concern:

Be it known that I, JULIA LUEDERS, a citizen of the United States, residing at St. Louis, in the State Missouri, have invented and produced a new and original Design for Chairs, of which the following is a specification, reference being had to the accompanying drawing, forming part thereof, and which is a perspective view of my chair.

10 1 represents the platform of a chair having rectangular connecting pieces 1 and side pieces, 1¹, having inclined front and rear portions 1¹.

12 2 represents seat-supports, rounded at bottom.

15 2¹ is an ornamental front strip beneath the seat 3.

7 represents a drawer beneath the strip.

8 represents springs on the inner side of the side pieces and supports.

4 represents arm-rest boxes in the shape of 20 a parallelopiped, projecting beyond the outside of the supports, with the exception of their inner sides, 4¹.

6 represents padded or rounded lids to the boxes. 25

5 represents the back.

I claim as my invention—

The design for a chair herein shown and described, comprising a seat portion, 3, front strip, 2¹, rounded side portions, 2, arm-rest boxes 4, in the shape of a parallelopiped, projecting from the tops of the side portions, having rounded lids 6, and a drawer, 7.

JULIA LUEDERS.
